HEATING DEVICE.

1,072,728.

Specification of Letters Patent. Patented Sept. 9, 1913.

Application filed April 30, 1908. Serial No. 314,483.

To all whom it may concern:

Be it known that I, Franc D. Holdsworth, a citizen of the United States, residing at Claremont, in the county of Sullivan and State of New Hampshire, have invented an Improvement in Heating Devices, of which the following description, in connection with the accompanying drawings, is a specification, like letters on the drawings representing like parts.

My invention relates to heating devices, the illustrated embodiment thereof being intended more particularly for the reheating of compressed air which is a common practice where the latter is employed as a source of power.

My invention has more particularly for its object the provision of a reheater having the utmost simplicity and economy of construction together with high efficiency of operation.

My invention will be best understood by reference to the following description, when taken in connection with the accompanying illustrations of specific embodiments thereof, while its scope will be more particularly pointed out in the appended claims.

In the drawings, Figure 1 is an elevation partially in section showing a reheater embodying one form of my invention; Fig. 2 is a plan of one of the terminal sections of the reheater shown in Fig. 1; Fig. 3 is an end elevation of the same; Fig. 4 is a section in plan on the line 4—4 in Fig. 3; Fig. 5 is an enlarged detail of the threaded coupling which unites adjacent sections; Fig. 6 is an elevation partially in section showing a modified form of reheater; Fig. 7 is a plan only of the end sections of the reheater shown in Fig. 6; Fig. 8 is an end elevation of the same; Fig. 9 is a sectional elevation taken on the line 9—9 of Fig. 7, and Fig. 10 is a sectional detail showing the ends of the tie-rods.

Referring to the drawings and more particularly to the specific embodiment of my invention illustrated in Figs. 1-5, I have there shown a reheater for compressed air adapted to receive the compressed air from the source of supply and, after imparting to it the necessary heat, to deliver it to the power consuming apparatus. The reheater is supported upon a base *a* of cast iron; or any other suitable material, which supports

a grate *b* and a cylindrical casing or base ring *c* lined with fire brick *c'*. There is thereby provided within the base an ash pit, access to which is had through the hinged door *a'* and, above the grate a fire pot, access to which is had through the hinged door *c''*. The fire may therefore be fed through the door *c''*, the grate oscillated by the lever *b'*, and the ashes removed through the hinged door *a'*, as is usual in an ordinary furnace.

Surmounting the base ring is a retaining ring *d* which acts to hold the fire brick in place and also to support the overhead main outer cylindrical casing and the contained heating sections. The outer shell or casing *e*, which is constructed preferably of sheet steel, rests at its lower edge upon the retaining ring and is provided with a thick lining of asbestos *e'*, or other suitable fire-proof, non-heat-conducting material extending within the casing substantially its entire length.

The products of combustion in passing upward come in contact with the walls of the successive heating and conducting sections and finally enter a conical smoke bonnet at the top of the heater. This smoke bonnet comprises a cast iron or other ring *f*, which rests upon the top edge of the casing and is itself surmounted by a steel or other suitable casing *f'* in the general form of a truncated cone. The products of combustion pass outward through the top of the smoke bonnet through a flue *f''*, shown broken away in the drawings, but which may be of any desired length, to furnish suitable draft, the flue passage being controlled by an adjustable regulating damper *f''*, which may be adjusted and held at any desired angle for appropriately regulating the draft.

The heating surface for the compressed air is afforded by a series of superimposed cast iron heating and conducting sections which, in the illustrated embodiment of my invention, consist of duplicate end sections, reversely arranged, and other duplicate intermediate sections removably attached one to another. To increase or reduce the heating surface to any desired extent and therefore to provide reheating units of different capacities, it is therefore merely necessary to increase or reduce the number of interme-

diate sections and change the length of the main shell or casing. Each section presents a substantially similar circuitous heating conduit to the compressed air with an inlet 5 from the preceding section and an outlet to the succeeding section, the air in passing from end to end of the conduit afforded by the successive sections being brought in contact with the highly heated walls thereof.

10 Referring first to the construction of the top and bottom sections, which, as above stated, are duplicates, but reversely arranged, these are provided with flanged openings or nozzles g , the lower one of which 15 extends through the casing and the asbestos packing at one side of the re heater and is connected to the source of compressed air supply, and the upper one of which extends through the opposite side of the casing near 20 the top thereof and is adapted to be connected with the air consuming means. The remaining portion of the section presents a generally annular conduit g' into which the air enters through the nozzle g (Fig. 4) and 25 separates into two branched paths g^2 and g^3 . This ring-like or annular section, however, is bridged (Fig. 2) at g^4 so as to present a cross passage for the air, this cross passage being provided (Figs. 1 and 4) with a partition g^5 which extends diagonally and downwardly so as to create in the bridged portion 30 two separate chambers g^7 and g^8 , the former opening to the conduit entrance and the latter to the terminal part thereof. The sections are provided at the top and bottom 35 faces with centrally arranged hubs or bosses g^9 , having interiorly pipe-threaded openings, the location of these threaded openings being such that the lower one has connections with the chamber g^7 and the upper 40 one with the chamber g^8 . These sections being symmetrical with reference to a central horizontal plane, a duplicate of the lower section has merely to be reversed in position 45 to provide the upper section.

The intermediate sections are almost identical in construction with the end sections, save that they are without the nozzle g , the air entering and leaving them through their 50 central lower and upper openings respectively. The lower section of the re heater has its lower central opening closed by the threaded plug g^9 . Resting upon the upper boss of the lower section is the next adjacent 55 intermediate section and effectively secured thereto by the threaded annular nipple g^{10} (Fig. 5). The latter has tapered pipe threads at each end and is first screwed into the lower section by a spanner or other tool 60 engaging the interior lugs g^{11} . The upper section is then screwed down upon the projecting tapered threaded end of the nipple. Successive sections are fastened one upon another in similar fashion.

65 The air entering at the inlet nozzle on the

lower ring first branches into two streams and again re-unites in the chamber g^6 . From here it passes upward through threaded nipple g^{10} into the chamber g^7 of the superposed section. From the chamber g^7 it again 70 separates and passes around the section, reuniting again in the chamber g^8 , from whence it passes to the next succeeding section, and so on, repeating this circuitous movement within the highly heated walls of 75 the successive sections, until it finally emerges from the outlet nozzle on the upper ring, the upper central opening of which is closed by a threaded plug g^{12} .

80 Although the sections are shown in registration one with another, that is to say, with the bridged portions lying in the same direction, it will be obvious that any precise relation of the kind is not necessary for the air enters and leaves each section centrally. 85 As a matter of fact the threads upon the threaded couplings can seldom be so cut as to bring the sections into any alining relation when they are each screwed to a seat.

90 The main conduit portion of each section is secured at intervals by ribs h , to a surrounding annular shell h' , herein in the form of a ring-like inclosure, which, as will be seen from Fig. 1, is a total width or 95 height somewhat less than the total distance between the opposite bearing surfaces upon the central bosses of the section, so that with the central bosses of adjacent sections in contact there is left a slight clearance between the adjacent edges of the rings.

100 When assembled, the ring of the lowermost section rests upon the retaining ring d . Each successive section is supported by its predecessor through the central bosses, the rings of the several sections when the latter 105 are positioned forming an almost but not quite continuous cylindrical surface of somewhat less diameter than the steel casing and between which and the casing is held the asbestos lining. Other outwardly directed 110 radial lugs h^2 are provided upon the rings h' , which lugs reach nearly to the casing. When the sections are assembled said ribs serve to center the sections in the casing and bring them into longitudinal alinement.

115 To bind the entire structure together longitudinally, the base of the re heater is exteriorly provided with four lugs j , two of which are shown in Fig. 1, these being in vertical alinement with four similar lugs j' 120 upon the smoke bonnet ring. When the sections have been assembled and the casing and lining placed in position, tie-rods j^2 with threaded ends are passed through these lugs and nuts screwed over the ends firmly to bind all parts together and in position. Two of these tie-rods oppositely located are provided with eyes j^3 at their upper ends so that hoisting tackle may be attached and the entire re heater readily moved from one place 125 130

to another by any suitable hoisting apparatus.

Owing to the unequal expansion of different parts of the apparatus and the high pressures which are employed with the re-heated air, it has heretofore been necessary in commercial reheaters with which I am familiar to make special provision in avoidance of leakage through excessive expansion.

10 In the described reheater, however, the sections, which are heavily constructed with the joints solid and well protected, are perfectly free to expand or contract with any possible temperature variations without 15 producing the least strain upon the structure which would tend to weaken the joints or cause leakage thereat.

The heating efficiency of the described structure is high since practically all of the 20 heating surface is availed of. The bridging conduit g^4 in each section acts as a baffle to spread the products of combustion by partially obstructing the central opening in the sections and thereby directing such 25 products of combustion laterally and causing them to pass outside of the annular conduits and between the latter and the annular inclosing rings, thereby causing a very effective and general distribution of the applied heat.

It will be evident that reheaters of widely 20 different capacities may be constructed, as above stated, by merely varying the number of intermediate sections and the length of 25 the outer casing. Another important advantage is that if the heating conduit burns out or bursts at any point, it may be quickly but effectively repaired by substituting a new section at that point, which can be done 30 with but little expense and delay.

In Figs. 6-10, inclusive, I have shown a modified form of my invention, which is substantially the same as that already described except for the construction of and mode of fastening together the sections. The sections, however, while comprising as before duplicate end sections and other duplicate intermediate sections, supported one upon the other, are held together by 40 four tie-rods h , which pass transversely the entire series of sections through openings formed in each, in upper and lower bosses. These bosses and openings for the intermediate sections are arranged in pairs. On 45 one side of the section there is provided (Figs. 6, 7 and 9) a pair of large bosses l , through which are openings l' leading to the interior annular conduit, said openings being of considerably greater diameter than 50 the tie-rod which passes therethrough. The corresponding pair of bosses on the opposite side of the section and the remaining pair of bosses on the same side of the section are of smaller diameter and provided with 55 openings just sufficient to permit the pas-

sage of the tie-rods therethrough without permitting leakage of air. The remaining pair of bosses and openings in the opposite side of the section are of enlarged diameter.

The upper and lower sections are provided at their upper and lower sides, respectively, 70 with bosses l^2 (Fig. 9) through which the tie-rods pass with a fairly tight fit and at their threaded ends they are secured by the nuts shown. The bosses upon the lower 75 section are counter-bored to receive the threaded plugs l^2 which prevent escape of air at that point.

To provide for expansion the tie-rods project above the upper section and are extended through the smoke bonnet, having each at its upper end a nut and washer resting upon the stiff coiled steel spring m , which spring bears upon a washer m' the latter resting on the sleeve m^2 , which in turn rests upon the upper heating section. When the structure is initially assembled 85 the nuts are screwed down to compress the springs and bind the sections tightly together, the springs, however, yielding when necessary to permit the expansion of the sections. The temper of the springs is preserved by locating them outside of the smoke bonnet and removed from the heat of the fire. To prevent the escape of air about 90 the tie-rods where they pass through the upper section, the inclosing sleeves n , threaded into the bosses l^2 of the section, are provided, the said sleeves being covered by the threaded cap n' .

The path of the air through the successive sections will be plain from the description and drawings. Entering the inlet or nozzle of the lower section the air separates, as before, into two streams which pass to the 95 opposite side of the section, and ascend to the upper section through the large sized openings about the tie-rods. These larger 100 openings in the bosses are arranged alternately on opposite sides of the section and the successive sections are reversed in position so that the air after entering one section travels horizontally in one direction, but on entering the next section travels 105 reversely, the complete course of the air from bottom to top taking place in a somewhat 110 zig-zag path. The joints between the adjacent sections, if desired, may be packed in any suitable way to prevent leakage.

The main body portion of the sections being substantially annular in form, there would naturally be left an unobstructed central opening presenting a direct central path for the products of combustion. One or more of the intermediate sections therefore 115 is preferably provided with a plurality of 120 interiorly projecting lugs o only one of which is shown in Fig. 6, to which may be bolted a baffle plate o' acting to prevent the 125 hot gases from the fire from passing directly 130

through the central openings in the sections. This serves as baffling means to cause the better general dissemination of the hot gases.

While I have described my invention as embodied in a re heater for compressed air and, in connection therewith, the same possesses marked and important advantages, certain features thereof may be employed in other connections. My invention therefore is not limited to the specific application thereof here illustrated, or to the particular details, of form, or relative arrangement of parts here shown but extensive deviations therefrom may be made without departing from the spirit thereof.

Having thus described my invention, what I claim new is,

1. A compressed air re heater comprising a base, a combustion chamber upon said base, a cylindrical casing surmounting said combustion chamber, a smoke bonnet and flue above said casing, a plurality of heating and conducting sections between the fire box and the smoke bonnet and within the casing, said sections comprising duplicate top and bottom members reversely arranged relative to one another and respectively provided with outlet and inlet openings, and intermediate duplicate sections mounted one above the other, each intermediate section having a circuitous conduct portion with an inlet from the preceding section and an exit to the succeeding one and means for separately and removably securing each section to the one or ones adjacent thereto.

2. An air re heater comprising a casing, a combustion chamber adjacent the lower end thereof, a plurality of substantially annular heating and conducting sections supported one above another and above the combustion chamber, said sections having each an inlet connection with the preceding section and an outlet connection with the succeeding one from bottom to top, said section including end sections, a cylindrical shell united to each annular section but of greater diameter than the latter, and a non-conducting lining between the casing and the outer walls of said several shells.

3. A heating device having an upright casing provided with a combustion chamber adjacent the lower end thereof, a smoke bonnet, a plurality of separate heating conduit sections having an air inlet and an air outlet and supported one upon another within said casing and above said combustion chamber, means for separately and removably securing said sections together and tie-rods binding together said smoke bonnet and said combustion chamber.

4. A section for a sectional heater comprising a main conduit portion provided with an inlet and an outlet passage adapted when the said section is in position for presentation to the next preceding and succeeding

sections respectively, said conduit section presenting a circuitous passage between the said inlet and outlet openings, and a shell surrounding said main conduit portion united thereto at intervals.

5. A section for a sectional heater comprising a substantially annular conduit portion and a surrounding cylindrical shell united thereto at intervals.

6. A section for a sectional heater comprising an inner conduit portion, an outer shell embracing the same united thereto at intervals, and a plurality of outwardly directed radial lugs secured to said shell.

7. A heater having a casing, a non-conducting lining therefor, a plurality of conduit sections provided each with an inclosing shell united to said section at intervals, and carrying means engaging said lining to prevent relative displacement.

8. A heating device having a casing, a plurality of removably attached conduit sections secured one to another, said sections comprising end sections with air outlet and inlet openings respectively, and duplicate connected intermediate sections, and a surrounding shell secured to each section to form a substantially continuous cylindrical casing within the main casing.

9. A heater having an upright casing, a base member upon which said casing rests, and a plurality of conduit sections arranged one above another within said casing, said sections having a surrounding shell attached thereto, the lowermost section resting upon said base member through its shell and the upper sections resting each upon the preceding section.

10. A section for a sectional heater comprising a main conduit portion provided with engaging faces on its opposite sides for engagement with the corresponding faces on the adjacent sections when in place, and a surrounding shell connected thereto at intervals, the width of the surrounding shell being less than the width of the conduit section between opposite faces.

11. A re heater for compressed air comprising a casing with a combustion chamber, and a plurality of conduit sections presenting a circuitous conduit to the compressed air exposed to the heat of the products of combustion, said series of attached conduit sections being supported at one end but capable of an expansive movement in the opposite direction.

12. A heater having a casing, a combustion chamber and an air heating and conducting conduit comprising separate but centrally attached sections adapted to expand freely in the direction of their attachment.

13. In a device of the type described, a heating section provided with a plurality of projecting ribs and a band secured adjacent

- the end portions of said ribs, said heating section having a conduit portion provided with oppositely directed inlet and outlet openings.
- 5 14. In a device of the type described, a ring-like heating section having a conduit extending circumferentially about said section, said section being provided with a plurality of ribs extending radially from the circumferential portion of the section, and a band or ring secured to said ribs adjacent the outer portions thereof to provide clearance between said band and the circumferential portions of said conduit.
- 10 15. In a device of the type described, a casing, a combustion chamber and a plurality of heating and conduit sections centrally attached one to another and provided with communicating passages through the central attachments, ribs attached to the peripheral portion of said sections and bands secured to said ribs, the band of one of the lower sections resting upon the top of the combustion chamber to be supported thereby, and said lower and upper sections having an air inlet and an air outlet, respectively.
- 15 16. In a device of the type described, a casing, a combustion chamber and a plurality of heating and conduit sections centrally attached one to another and provided with communicating passages through the central attachments, ribs attached to the peripheral portion of said sections and bands secured to said ribs, the band of one of the lower sections resting upon the top of the combustion chamber to be supported thereby, said lower and upper sections having an air inlet and air outlet respectively, and a packing of non-conducting material between said bands and said casing.
- 20 17. In a device of the type described, a casing having a combustion chamber, an air heater comprising a plurality of connected and communicating ring like conduit sections arranged above said combustion chamber and adapted to be heated thereby, each of said sections having an annular conduit portion through which air is adapted to pass and one or more centrally arranged apertures or orifices for the combustion products, a plurality of radially extending ribs, extending outwardly from the circumferential portions of each of said sections, a band or outer shell secured to said ribs adjacent the outer ends thereof to provide a plurality of peripheral passages for said combustion products.
- 25 18. In a sectional heater, a section comprising a hollow ring like member adapted to be connected with similar members and having centrally located means for connecting said members therewith, an outer shell connected with the peripheral portions of said member to provide clearance space between the same and said member and centrally located means forming a bridge between the walls of said member and presenting apertures extending through said member from one to the other of its faces.
- 30 19. A heater having a casing and a combustion chamber and a plurality of substantially annular air heating and conducting sections centrally but removably attached to one another and provided each with an air inlet passage through the central attachment to the preceding section, and an air outlet passage through a point of its attachment to the succeeding section, the annular walls of said section having circuitous conducting passages through which only the said inlet of each section is connected with the outlet of that section, and end sectional members detachably connected centrally each to its adjacent section, the inlet and outlet end sections having respectively lateral inlet and outlet passages in the side annular walls of the section for connection each to a conduit or pipe, whereby the structure may be increased or decreased as to capacity by introducing additional intermediate sections while employing the same end sections and preserving the circuitous path for the medium to be heated.
- 35 20. As a new article of manufacture, an end section for a sectional heater comprising a substantially annular member having a central axial opening and a lateral conduit opening into the annular walls of the member transverse to the axis of the section and communicating with the central axial opening by circuitous conducting passages formed in the said annular walls of the member.
- 40 In testimony whereof, I have signed my name to this specification, in the presence of two subscribing witnesses.
